United States Patent Office

Des. 206,098
Patented Oct. 25, 1966

206,098

HINGED COMPARTMENTED CONTAINER

John Donald Bostrom, Niles, Ill., assignor to Illinois Tool
Works Inc., Chicago, Ill., a corporation of Delaware

Filed Mar. 15, 1965, Ser. No. 84,260

Term of patent 14 years

(Cl. D58—13)

Fig. 1

Fig. 2

Fig. 3

Fig. 4

Fig. 5

FIG. 1 is a perspective view of a hinged compartmented container showing my new design as it appears in opened position, the upper portion being similarly compartmented;

FIG. 2 is a side elevational view thereof as it appears in closed position;

FIG. 3 is a view of the bottom container half taken along line 3-3 of FIG. 2;

FIG. 4 is a top plan view of the container; and

FIG. 5 is an end view thereof.

I claim:

The ornamental design for a hinged compartmented container, as shown and described.
